F. STREET

GAS LIGHTING DEVICE

Filed June 25, 1921

Fig. 1.

UNITED STATES PATENT OFFICE.

FRED STREET, OF PHILADELPHIA, PENNSYLVANIA.

GAS-LIGHTING DEVICE.

Application filed June 25, 1921. Serial No. 480,437.

To all whom it may concern:

Be it known that I, FRED STREET, a citizen of the United States, residing in Philadelphia, Pennsylvania, have invented certain 5
5 Improvements in Gas-Lighting Devices, of which the following is a specification.

My invention relates to improvements in mechanical lighting devices for gas burners, one object of my invention being to provide 10 a lighting device which is applicable to gas burners irrespective of type or condition of use. A further object is to provide means including a pilot light which except at the times it is performing its function of 15 lighting the burner, remains unlighted. A still further object of the invention is to provide means incorporated in the said lighting device for governing the position of the valve which controls the flow of gas 20 to the burner to give either high or dim light as desired. A further object is to provide a device of the nature specified which is adaptable to gas burning fixtures of any type and which possesses certain features of 25 construction making the device comparatively simple and of low cost of manufacture. It is further contemplated to provide the device with certain shock absorbing means rendering it in operation substantially noiseless and which greatly reduces 30 the wear and tear upon the device due to the shock in stopping the moving parts.

In the attached drawings:

Figure 1, is a front elevation of a device 35 made in accordance with my invention;

Figs. 2 and 3, are respective side elevations of the device, and

Figs. 4, 5, 6 and 7, show the various positions of the valve, which correspond to the 40 positions of the operating lever.

With reference to the drawings, my device comprises in substance a hollow body portion 1 having means at top and bottom thereof for attaching said body in the gas line, said body in the present instance being shown with the gas pipe 2 threaded into the bottom thereof and having threaded into the top a gas burner 3 of well known type. The said body 1 in the present instance is of 45 substantially L-shape, and has formed in the lateral portion thereof a tapered valve opening in which is seated a conical valve 4, which valve has a passage 5 extending therethrough, whereby in given positions of

the valve gas is permitted to flow through 55 the central passage 6 of the body portion, while in other positions of the valve the passage of gas from the pipe 2 to the burner 3 is prevented. The valve 4 has also extending therethrough from end to end a lateral 60 channel 7 which communicates with the passages 5, and there is provided at each end of the valve a threaded counterbore 8 and 9 respectively adapted to receive screws 10 and 11, said screw 10 functioning to retain 65 the said valve within the body portion 1, and there being interposed between the head of the screw and the said body portion a washer 12 which is adapted to slide freely 70 on the face of the body portion to permit 75 free rotation of the valve therein.

Extending radially from the channel 7 to the periphery of the valve is a channel 13, the outer end of which is adapted to register with a channel 14 extending upwardly through the top of the body portion 1, and said latter channel 14 is adapted to form a continuous part of a channel 15 which extends upwardly through a bracket support 16, which latter is attached to the 80 body portion 1 and held in place by a divided strap 17, which extends around the outer end of the lateral portion of the body 1, and which has its ends held together to cause the said strap to grip the body member by means of a screw 18.

At the top of the bracket 16 is rotatably mounted a star wheel 19 of well known form which has secured thereto a tooth or corrugated wheel 20, said star and wheel being 90 carried by a spindle 21 fixed in a lug 22 of the bracket, while established in a second lug 23 at the top of the bracket and occupying a suitable recess formed therein is a piece of flint 24 which is adapted to bear 95 against the periphery of the toothed wheel 20, so that when the latter is rotated, a spark is formed in the well known manner. The said lug 23 has a laterally threaded extension 25 through which the said recess or channel, in which the flint 24 is established, extends, and a cap 26 is threaded to said extension 25 and confines within said extension and between the rear end of the flint 100 and the head of the said cap a spring (not shown) which exerts a pressure tending to force the said flint forwardly against the periphery of the wheel 20.

Pivottally mounted at the forward end of the horizontal portion of the body 1 is an operating member 30, said member comprising an arm 31 which constitutes the operating lever of the device, and an extension 32 which is adapted to engage a pivotally mounted and substantially hook-shaped element 33 carried by a second member 34 pivotally secured by means of the said screw 11 between the member 30 and the forward face of the body portion 1. The said member 34 comprises a rearwardly extending arm 35, which has attached to the end thereof one end of a coiled spring 36, the other end of said spring being secured to the rearward extension 37 of the spindle 21, which carries the star wheel 19, said spring 36 tending to retain the said member 34 in a given normal position, as shown in Fig. 1. 10 The central portion of the arm 31 is pressed outwardly to form a laterally extending arm 38 upon the member 30, and this arm 38 has secured to the end thereof one end of a spring 39, the other end of which spring is secured in suitable manner to the said extension 37 of the spindle 21, said spring 39 exerting a force upon the said arm tending to retain the arm 31 in an elevated position and the member 30 in the position shown in Fig. 1. The said element 33 is pivoted at 41 to the member 34, and normally tends to assume the position shown in Fig. 1, with the forward end thereof lying down in front of the extension 32 of the member 30, so that when the arm 31 is moved downwardly to rotate the member 30 in a counter-clockwise direction, (see Fig. 1), the said extension 32 which occupies the same plane as the element 33 engages the inner edge of said element and carries the said member 34 forwardly. 20 25 30 35 40 45 50 55 60 65 70 75 80 85 90 95 100 105 110 115 120 125 130

The element 33 has a rearwardly extending roller 42 which extends through an aperture 43 in the member 34, and which, when the member 34 has been carried in the manner previously stated in a counter-clockwise direction around the pivot 11, is adapted to engage the outer end of a cam extension 44, upon the bracket 16, said cam extension preventing further downward movement of the said element 33, and as the movement of the member 34 persists, causing the said element 33 to be elevated on its pivot 41, with respect to the said member 34 until the extension 32 of the member 30 is carried free of the lower hooked end of the element 33, whereupon, the member 34 being released from the element 30, the spring 36 acts to return it to its original normal position shown in Fig. 1. In this rearward movement of the member 34, the outer edge of the element 33 rides over the outer edge of the extension 32, which so elevates the element 33 that the rearward extension 42 is brought into engagement with one of the

arms of the star wheel 19, this engagement, due to the movement of the element 34, causing a partial rotation of the star wheel and of the wheel 20, and creating a spark by the friction between the wheel 20 and the aforementioned flint, this spark being formed adjacent the upper end of the channel 15, as most clearly shown in Fig. 1. 70

Upon release of the arm 31, the member 30 tends to return to the normal position shown in Fig. 1 under the action of the spring 39, and when this return is made, the rear edge of the extension 32 is adapted to engage an extension 45 of the element 33, and thereby to swing the said arm in a counter-clockwise direction around its pivot 41 to return it to the normal position, in which it is shown in Fig. 1, providing it has not already returned to this position under the action of gravity. This extension 45 functions particularly when the device is employed in such connection that it is required to be inverted from the position illustrated in the drawings, at which time this arrangement is necessary to return the element 33 into position to be re-engaged by the extension 32 when the member 30 is again oscillated. 85 90 95 100 105 110 115 120 125 130

At the under side of the said member 30 is an extension 48 which turns rearwardly and extends across the face of the strap 17, as best shown in Fig. 2, said arm 48 having a slot 49 formed therein in which is established a pin or stud 50, said stud being retained in said slot by means of a head 51 and a washer 52 secured to said stud on the inner side of the arm 48, and there being a spring 53 confined between the head 51 and the outer face of the arm 48, which spring by frictional engagement with the said arm tends to retain the said stud against lateral movement in the slot. 105

The strap 17 has secured in suitable manner as by the screw 18 to one side thereof adjacent the extension 48, a plate 17^a which is recessed or perforated, as shown at 55 in Fig. 2, and the inner end of the stud 50 is adapted to occupy the said recess and to be shifted laterally in the slot 49 by contact with the sides thereof. The said cam recess 55 is best shown in Fig. 2, and is of general V-shape, having in the present instance three recesses, 56, 57 and 58, at the top thereof and extending at the bottom into the point of the V. Located substantially centrally of the recess 55 is an elevation 60, which has in the top thereof, in the present instance, recesses 61 and 62, the point which separates the said recesses 61 and 62 rising upwardly and being disposed substantially equidistant between the two points which define the recess 57, the said outer points of the recesses 61 and 62 being similarly located respectively with regard to the recesses 56 and 58. When the arm 31 is carried downward, the 130

- arm 48 is correspondingly elevated, the said stud rising upwardly along the right hand wall (see Fig. 2) of the recess 55, and finally entering the recess 56 at the top. The said recess 56 is so formed that after the stud has entered the recess to the top thereof and the arm 31 is released, the stud in passing downwardly with the arm 48 will enter the recess 61 of the elevated portion 60. 5
- 10 A further upward movement of the arm 48 will cause the stud to enter the recess 57, which has the effect of again shifting the said stud to the left, so that when the arm 48 again moves downwardly, the stud enters the recess 62. A further upward movement of the arm 48 will bring the stud into the recess 58, which carries it to the left-hand wall, still having reference to Fig. 2, 15 of the cam recess, and the next following downward movement of the arm 48, the stud passing downwardly along the said left-hand wall, will permit the arm to pass down to the extreme low or normal position, as shown in the figures. 20
- 25 When the parts occupy the positions shown in the drawings, in Figs. 1, 2 and 3, the stud occupying the lower point of the recess 55, the valve 4 is in substantially the position in Fig. 4, with the passage 5 disposed laterally of the passage 6, whereby the gas in the pipe 2 is prevented from passing upwardly to the burner 3. When the arm 31 is moved downwardly to the extreme low position, the said stud will occupy the recess 30 56, and in this position of the lever 31, the valve 4 occupies the position illustrated in Fig. 5, with the passage 5 in alignment with the passage 6, whereby gas is permitted to flow upwardly to the burner. In this 35 position of the valve, also, the channel 13 is carried in a substantially vertical position so that the upper end thereof registers with the lower end of the channel 14 whereby gas is permitted to flow through the 40 channels 7 and 13, and through the channel 15 to the top of the bracket 16. In the downward movement of the arm 31 to bring the valve into this latter position, the element 33 is released from the projection 32, 45 in the manner previously described, just after the valve is brought into position to open the passages permitting the flow of gas through the channel 15 and to the burner 3, so that the spark generated, as previously 50 described, by the rotation of the star wheel 19, will have the effect of igniting the gas flowing from the top of the channel 15, thus forming a pilot light, which in turn will 55 ignite the gas flowing from the burner 3. 60 Upon release of the arm 31, the spring 39 acts to turn the member 30 in a clockwise direction, this movement being limited by the stud 50 entering the recess 61 in the elevation 60, and in this condition the valve 65 4 is as shown in Fig. 6, permitting the free

flow of gas to the burner. The valve, however, has moved sufficiently to carry the channel 13 out of coincidence with the channel 14, thereby cutting off the pilot light and the flow of gas to the channel 15. 70

If now it is desired to make the light dim, a further downward movement of the arm 31 is necessary, and a consequent elevation of the said arm by means of the spring 39 so as to bring the stud 50 into the recess 62, in which position of the parts the valve assumes the positions substantially as shown in Fig. 7, with the gas burner partially cut off. By again carrying the arm 31 downwardly and releasing it, the parts are returned to 80 the position shown in Fig. 1, in which case the valve 4 again shuts off the flow of gas to the burner.

In order to eliminate as far as possible the jar due to the springing back of the member 34 after release from the member 30, I provide at the rear of said member 34 a spring arm 65, the lower end of which arm as the member 34 springs backwardly to its normal position strikes against the side 90 of the arm 48, which is at the moment in an elevated position, the jar of the contact being broken by the action of the spring 65. 85

I also provide upon the cord or chain 66 which is attached to the arm 31 and by means of which the device is actuated, a link 67 which is interposed between the upper end of the chain 66 and the arm 31, said link comprising a hollow cylinder 68 having established therein a plunger 69 with 100 an arm extending downwardly through the bottom of said cylinder and attaching to the chain 66, said cylinder 68 being secured to the end of the arm 31 by means of a suitable link 70. Confined between the 105 bottom of the cylinder 68 and the underside of the plunger 69 is a spring 71, through which spring the pull upon the chain is transmitted to the arm 31. This device further relieves the shock due to the 110 sudden contact of the member 34 with the arm 48 in the manner specified.

One big advantage of the described construction is the fact that I am able to keep the lighting device well away from the 115 burner or mantle, since the pilot light may be projected to a considerable distance, and there is as a consequence no possibility of damage to the apparatus from the heat of the burner. I am, for similar reasons, enabled to provide a lighting device of standard construction which without alteration may be applied to any kind of fixture. It will further be noted that the outer mechanism of the device is detachable from the 120 body 1, and that as a consequence the said body may be employed, with possible modifications of the mechanism, to suit particular conditions of use. It will be apparent for example that the cam recess 55 may be 125 130

varied as by elimination of the recess 62, which would do away with the low light provision, and still other modifications are possible within the scope of the invention.

5 I claim:

1. In a device of the character stated, the combination with a burner element, of a valve controlling the flow of gas to the burner, means operatively associated with the valve for igniting the gas at the burner, means providing for manual movement of the valve into open position, mechanical means tending to return the valve to closed position, and means for releasably retaining the valve in the open position.

10 2. In a device of the character stated, the combination with a burner element, of a valve controlling the flow of gas to the burner, means operatively associated with the valve for igniting the gas at the burner, means providing for manual movement of the valve into open position, mechanical means tending to return the valve to the closed position, means limiting the movement of the valve in both directions, and means for releasably retaining the valve in a position intermediate the said limits.

15 3. In a device of the character stated, the combination with a burner element, of a valve controlling the flow of gas to the burner, means operatively associated with the valve for igniting the gas at the burner, means providing for manual movement of the valve into open position, mechanical means tending to return the valve to closed position, means limiting the movement of the valve in both directions, and means for releasably retaining the valve in a plurality of positions intermediate said limits.

20 4. In a device of the character stated, the combination with a burner element, of an auxiliary burner constituting a pilot for the said first burner, a valve adapted in one extreme position to shut off the flow of gas to the burner and the pilot and in the other extreme to admit gas both to the pilot and burner, an intermediate position of said valve admitting gas to the burner but not to the pilot, means operatively associated with the valve for igniting the pilot, means providing for manual movement of the valve into the pilot-opening position, mechanical means tending to return the valve to burner closing position, and means for releasably retaining the valve in the said intermediate position.

25 5. In a device of the character stated, the combination with a burner element, of an auxiliary burner constituting a pilot for the said first burner, a valve adapted in one extreme position to shut off the flow of gas to the burner and pilot and in the other extreme to admit gas to both the pilot and burner, said valve in intermediate positions thereof admitting gas to the burner in vary-

ing degrees of volume but not to the pilot, means operatively associated with the valve for igniting the pilot, means providing for manual movement of the valve into the pilot-opening position, mechanical means tending to return the valve to burner closing position, and means for releasably retaining the valve in a plurality of said intermediate positions.

30 6. In a device of the character stated, the combination with a burner element, of a valve controlling the flow of gas to the burner, mechanical means tending to retain the valve in the closed position, an operating element providing for manual movement of the valve against said mechanical retaining means to open the valve, and means releasable by manipulation of the said operating element for retaining the valve in the extreme open position and in an intermediate position in opposition to said retaining means.

35 7. In a device of the character stated, the combination with a burner element, of a valve controlling the flow of gas to the burner, mechanical means tending to retain the valve in closed position, an operating element providing for manual movement of the valve into open position, and means releasable by manipulation of the said operating element for retaining said valve in the open position and in a plurality of partially open positions in opposition to said retaining means.

40 8. In a device of the character stated, the combination with a burner element, of a valve controlling the flow of gas to the burner, means operatively associated with the valve for igniting the gas at the burner, an operating element providing for manual movement of the valve into open position, a spring exerting a force tending to return the valve into closed position, and means associated with the valve and releasable by manipulation of the said operating element for retaining the valve in open position.

45 9. In a device of the character stated, the combination with a burner element, of a valve controlling the flow of gas to the burner, means operatively associated with the valve for igniting the gas at the burner, means providing for manual movement of the valve into open position, a spring exerting a force tending to retain the valve in closed position, a cam element relatively fixed with respect to the valve, and an element movable with the valve and adapted to engage the cam element, substantially as and for the purpose set forth.

50 10. In a device of the character stated, the combination of a movable valve element, means providing for manual movement of the valve in one direction, mechanical means tending to move the valve in the opposite direction, and means releasable by manipu-

lation of said manual moving means for retaining the valve against movement by said mechanical means.

11. In a device of the character stated, the combination with a valve element, of a spring tending to retain the valve element in closed position, means for retaining the valve element in open position, and a single operating member for both opening the valve and releasing the said retaining means to permit return of the valve element by the spring to closed position.

12. In a device of the character stated, the combination of a rotary valve element, means providing for manual rotation of the valve from an initial to a secondary position, a spring tending to retain the valve in the initial position, a plurality of means each releasable by manipulation of said manual rotating means for retaining the valve in different positions intermediate the initial and secondary positions, and means whereby successive manipulations of the manual means brings said retaining means progressively into operation.

13. In a device of the character stated, the combination of a rotary valve element, means providing for manual rotation of the valve from an initial to a secondary position, a spring tending to retain the valve in the initial position, a cam element relatively fixed with respect to the valve and comprising a plurality of recesses, and an element movable with the valve and adapted on successive manipulations of the said valve rotating means to progressively enter the said recesses whereby the valve is retained in positions intermediate the initial and secondary positions.

14. In a device of the character stated, the combination of a rotary valve element, means providing for manual rotation of the valve from an initial to a secondary position, a spring tending to retain the valve in the initial position, a cam element relatively fixed with respect to the valve and comprising a recess, an element movable with the valve and adapted after movement of the latter into the secondary position to enter the said cam recess whereby the valve is retained in a position intermediate the initial and secondary positions, and means operable by manipulation of the valve rotating means for releasing the said element from the recess.

15. In a device of the character stated,

the combination of a rotary valve element, means providing for manual rotation of the valve from an initial to a secondary position, a spring tending to retain the valve in the initial position, a cam element relatively fixed with respect to the valve and comprising a recess, a longitudinally slotted arm movable with the valve, an element established and movable in said slot and adapted to engage the cam element, cam means operable after movement of the valve into the secondary position for guiding the said slot element into the said cam recess, thereby retaining the valve in a position intermediate the initial and secondary positions, and cam means operable by movement of the valve toward the secondary position for guiding the slot element out of said recess.

16. In a device of the character stated, a body member adapted to be inserted in a pipe line and comprising a valve seat, a valve in said seat, mechanism carried by said body and comprising an element movable with the valve into an advanced position, a spring for returning the element to the normal retracted position, and means for breaking the shock of the return movement of said element.

17. In a device of the character stated, a body member adapted to be inserted in a pipe line and comprising a valve seat, a valve in said seat, mechanism carried by said body and comprising an element movable with the valve into an advanced position, a spring for returning the element to the normal retracted position, a stop determining the said retracted position, and resilient means for breaking the shock between the element and the stop on the return of the former to retracted position.

18. In a device of the character stated, a body member adapted to be inserted in a pipe line and comprising a valve seat, a valve in said seat, an operating lever attached to the valve, mechanism carried by the body and comprising a member adapted to be engaged by said operating lever and moved thereby into an advanced position with the valve, means for shifting the member to release it from engagement with said lever, and interengaging elements on said lever and member whereby the latter is shifted again into position to be engaged by the lever.

FRED STREET.
